(57) **CLAIM**

What is claimed is the ornamental design for a “modular fire pit”, as shown and described.

DESCRIPTION

FIG. 1 is a front perspective view showing the “modular fire pit” of Applicant’s invention.

FIG. 2 is a front elevation view of the “modular fire pit” of Applicant’s invention.

FIG. 3 is a back elevation view of the “modular fire pit” of Applicant’s invention.

FIG. 4 is a right side elevation view of the “modular fire pit” of Applicant’s invention.

FIG. 5 is a left side elevation view of the “modular fire pit” of Applicant’s invention.

FIG. 6 is a top view of the “modular fire pit” of Applicant’s invention; and,

FIG. 7 is a bottom view of the “modular fire pit” of Applicant’s invention.

In the Figures, the broken lines depict unclaimed portions of the modular fire pit and form no part of the claim.
